UNITED STATES PATENT OFFICE.

FREDDIE K. MARTIN, OF CHELSEA, OKLAHOMA.

OIL-BURNER.

1,089,938.

Specification of Letters Patent. Patented Mar. 10, 1914.

Application filed September 12, 1913. Serial No. 789,501.

To all whom it may concern:

Be it known that I, FREDDIE K. MARTIN, a citizen of the United States, residing at Chelsea, in the county of Rogers and State 5 of Oklahoma, have invented new and useful Improvements in Oil-Burners, of which the following is a specification.

This invention is an improved oil burner especially adapted for burning crude petroleum being also adapted for burning other liquid hydrocarbons, the object of the invention being to provide an improved burner of this kind which is extremely cheap and simple, the parts of which may 15 be assembled and disassembled and may be kept clean and in order.

The invention consists in the construction, combination and arrangement of devices hereinafter described and claimed.

20 In the accompanying drawing: Figure 1 is a vertical longitudinal central sectional view of a burner constructed in accordance with my invention. Fig. 2 is a vertical transverse view of the same on the plane 25 indicated by the line *a—a* of Fig. 1.

In accordance with my invention I provide an oil supply duct 1, which is a straight pipe and is provided at its outer end with an intake tubular arm 2 arranged at right 30 angles thereto and to which an oil supply pipe from a suitable reservoir is in practice connected. A steam jet pipe 3 is arranged in the oil supply duct 2, concentrically thereof and passes through an opening in 35 the arm 2. This steam jet pipe extends about half way through the oil supply duct 1.

A mixer 4 which is tubular in form and is of greater diameter than the oil supply 40 duct has a reduced inner end 5 provided with an opening through which the said oil supply duct extends and also has a reduced outer end 6 formed with a nozzle or jet tip 7. The mixer is slidably fitted on the oil supply 45 duct and may be adjusted longitudinally thereon and secured in adjusted position by means of a clamping screw 8. In the sides of the mixing tube 4 at points about midway between the ends thereof is a series of

air inlet openings 9. A cover sleeve 10 is 50 fitted on the outer side of the said mixer 4 and may be turned or moved to close the air intake openings to any desired extent.

In the operation of my improved burner steam from a boiler is supplied to the steam 55 jet pipe 3 and as it passes through the oil intake duct 2 creates the partial vacuum therein and hence causes oil as well as steam to be discharged into the mixer and also causes the oil to be atomized. Air is admitted to the mixer through the openings 9 and becomes commingled with the atomized oil to render the latter highly combustible and as the oil, air and steam issue from the mixer through the jet tip 7 the said mixture 60 is burned in a clear flame and without smoke. The heat caused by the flame and surrounding the burner in the furnace or other place where the burner is used also causes the burner to act as a retort and 65 vaporize and promote the combustion of the oil.

Having thus described my invention, I claim:

An oil burner of the class described comprising an oil supply duct having a feed arm at right angles thereto, a steam jet pipe arranged concentrically in said oil supply duct and extending through an opening in one side of the feed arm thereof, a tubular mixer of greater diameter than the oil supply duct and in which the latter is arranged, said mixer having a reduced inner end providing an opening through which the oil supply duct extends and being detachably fitted on said oil supply duct and being further provided with a reduced outer end provided with a jet tip, the mixer being further provided with air inlet openings at a point intermediate its ends and 90 means to vary the effective area of said air inlet openings.

In testimony whereof I affix my signature in presence of two witnesses.

FREDDIE K. MARTIN.
